UNITED STATES PATENT OFFICE.

ETHELBERT M. FRASER, OF YONKERS, NEW YORK, ASSIGNOR TO OTIS ELEVATOR COMPANY, OF EAST ORANGE, NEW JERSEY, A CORPORATION OF NEW JERSEY.

DRIVING-GEARING FOR ELEVATORS.

SPECIFICATION forming part of Letters Patent No. 762,698, dated June 14, 1904.

Application filed August 20, 1901. Serial No. 72,678. (No model.)

To all whom it may concern:

Be it known that I, ETHELBERT M. FRASER, a citizen of Canada, residing at Yonkers, in the county of Westchester and State of New York, have invented certain new and useful Improvements in Driving-Gearing for Elevators, of which the following is a specification.

My invention relates to certain improvements in driving-gearing adapted for use in hoisting mechanism in general, but more particularly to elevators, and while parts of the apparatus hereinafter described may be applied to hoisting-machines or to elevators of any class I have referred in detail to but one class of elevators and have shown and described a complete elevator operated with the "Fraser" rope-drive, as disclosed in United States Patent No. 610,481, granted to me September 6, 1898. As well known, with this class of elevators two pulleys are connected with a car, as by an endless cable, in such a way that when the pulleys are both running at the same speed the car will remain stationary, and when they are running at relatively different rates of speed the car will move either upward or downward. There is ordinarily a separate motor for driving each pulley, as electric motors, and the relative speeds of the pulleys may be varied by varying the speed ratios of the motors.

One object of my invention is to devise means for reducing the number of motors required in this class of elevators from two to one, thus producing a more economical and efficient system, especially where electricity is a motive power, since the one motor may be kept running at all times with a load where high efficiency is reached, while with two motors both are ordinarily running at the same time with waste of power.

Means should be provided for controlling the speed of the pulleys and for controlling the speed of each pulley, so that the pulleys may be operated at the same or relatively different speeds.

Another object of my invention therefore consists in providing mechanical means in the

form of a friction power-transmission gear for varying the relative speeds of the pulleys or whereby the speeds of the pulleys may be varied and then maintained at any desired ratio.

Another object of my invention is to provide a variable-speed mechanism suitable for elevators, by means of which changes of speed may be effected easily, smoothly, and efficiently.

It has heretofore been possible to transmit but small power with friction-gear, especially in elevator service; and an object of my invention is to produce a friction power-transmission gear suitable for heavy work.

Referring to the drawings, Figure 1 is a side elevation of an elevator embodying my invention. Fig. 2 is a side view, partly in section, of my power-transmission gear. Fig. 3 is a plan view, partly in section, on line $\alpha\alpha$, Fig. 2. Fig. 4 is a side view, partly in section, of part of the movable holder for the friction-rollers. Fig. 5 is a side view, partly in section, of a modification of my transmission-gear where opposite rotation of the driving and driven shafts is obtained.

In the drawings, A and B represent suitable pulleys or sheaves adapted to rotate in the same or opposite directions, as hereinafter described, A being keyed to a shaft A', shown as the driven shaft, and B being keyed to a shaft B', shown as the driving-shaft, to which is connected a suitable motor C, preferably an electric motor. Any suitable gearing may be used for connecting the motor to the driving-shaft, or it may be connected directly thereto; but for convenience a belt connection is shown between the motor and driving-shaft. A suitable constant connection between the pulleys and the car, as an endless cable D, is shown on the pulleys and passing over idle pulleys E and F upon the car G and counterweight Q, respectively, while a suitable connection, as by a hoisting-rope I, is made over sheaves K between the car G and counterweight Q.

In Fig. 1 the pulleys A B are adapted to

rotate in the same direction, and in order that the Fraser rope-drive shall operate in the usual manner to raise and lower the car it is necessary that the endless cable shall 5 be crossed before passing around one of the pulleys, as B, idle pulleys $a'b'$ being shown in a position suitable for the accomplishment of this purpose, the cable passing over these idle pulleys. Properly-grooved pulleys to 10 prevent interference and wear between the crossed parts of the cable should be used where it is necessary to cross the cable, as described, and a single or multiple cable may be employed, as desired, with grooved pulleys. By this arrangement if pulley A is rotating faster than B, A becomes the driving-pulley for the car and pulls the car down, while if B is rotating faster than A it becomes the driving-pulley, pulling the counterweight 15 down and the car up. When both pulleys are rotating at the same speed, the car is stationary. The electric motor C is shown as a variable-speed motor, the speed of which may be varied and controlled by any of the well-known means; but in this instance the motor is 20 shown with a rheostat R, preferably in the circuit of the field-coils, for varying the field magnetization, and thus the speed of the motor. 25

Upon each of the shafts A' B' are provided friction-disks b in sets M N, shown containing a plurality of disks each. These disks are preferably arranged with their faces parallel to each other and should be longitudinally 30

the driven shaft may be varied. When the rollers d d' are at equal distances from the shafts A B, the said shafts will rotate at the same speed; but when the rollers are moved 5 nearer the periphery of disks b on driving-shaft B', and consequently toward the center of disks b on driven shaft A', the driven shaft will be driven faster than the driving-shaft, and when the rollers are moved toward the 10 center of the disks on the driving-shaft the driven shaft runs slower than the driving-shaft.

I provide means on the car for controlling the relative speeds of the disks, and consequently 15 the relative speeds of the shafts A' B', thereby controlling the relative speeds of the pulleys A B. Suitable connections X are made between the corners of the holder H or from any part of the sides and ends thereof to 20 each other and to a suspended cable or connector Y, which passes over pulley Y' on the car and round a pulley X' beneath the transmission-gear and beneath the holder H to a suitable counterweight, as usual. The usual 25 crank or wheel Z is provided on the car for rotating pulley Y' in either direction, by which means it will readily be seen that the holder H may be raised or lowered on guides W to change the position of the rollers d d' on the 30 faces of the disks b.

As shown in Fig. 2, the rollers d d' instead of being constructed of one piece upon a spindle d^3 may be each constructed of a plurality of parallel revoluble disks upon spindles. 35 These parallel revoluble disks d^4 are arranged side by side upon a spindle d^3 and may be made of any suitable material, as steel, the object of this arrangement being to avoid the friction caused by some portion of the roller sliding 40 instead of rolling. Where but one roller d is used between each pair of disks, the driving and driven shafts will rotate in the same direction, and to cause opposite rotation of the said shafts it is only necessary to place two 45 rollers d between each pair of disks, as shown in Fig. 5, the supports e being made slightly wider, if necessary, for the accommodation of the two rollers, and where a transmission-gear is used with driving and driven shafts rotating 50 in opposite directions it is of course not necessary to cross the endless cable over one of the pulleys A B, as shown in Fig. 1.

While it is not necessary, I at the same time prefer to inclose my transmission-gear in a 55 suitable oil box or casing P, which may be filled with oil to increase the efficiency of the apparatus.

Since I have shown a single variable-speed motor for the driving-pulleys A B connected 60 to one of the pulley-shafts, as B', with a variable-speed power-transmission gear between the driving and driven shafts, the operation of which gear is controlled from the car, it will be seen that the speed of each pulley may

be varied and controlled, while any variations 65 in the relative speeds or speed ratios of the pulleys through the operation of the mechanical power-transmission gear may be controlled from the car.

The mechanical power-transmission gear is 70 independent of the motor, constituting a driving connection between the shafts A' B', and by it the speed of one of the pulleys, as that of A, may be varied, while that of the other, B, remains substantially constant. 75

Any constant connection may be made between the pulleys A B and the car, not necessarily an endless cable, and the car itself is only illustrative of what may be termed "a part to be operated," and the pulleys A B 80 may be driven in the same or opposite directions, according to the form of power-transmission gear used.

I am not to be understood as confining myself to the precise form of apparatus shown 85 and described, for in order to embody the broad principles of my invention any suitable means may be employed whereby a single motor may operate at the same or relatively different speeds two pulleys having constant connections with a part to be operated; nor do I 90 limit myself to the precise details of construction of the transmission-gear and operating mechanism therefor.

My variable-speed gear can advantageously 95 be utilized to change the relative speeds of any two parallel shafts, as in a lathe, in place of the usual cone-pulleys and gears. It is also particularly applicable to automobiles, especially those driven by gas-engines, as a substitute for gears, since a gas-engine operates most economically at substantially one speed, and it is desirable to control the speed of the vehicle without changing the speed of the motor. 100

Many other applications may be found for my transmission-gear, which will readily suggest themselves to those skilled in the art. 105

Without limiting myself to the precise details of construction of the parts shown, I claim 110 as my invention—

1. The combination in a driving-gear, of a motor, two pulleys and means of communicating motion from both of said pulleys to a part to be driven, means for driving one pulley from the other, and means for varying the speed thus imparted to the driven pulley, substantially as described. 115

2. The combination with a part to be operated, and a motor, of a power-transmission gear comprising driving and driven shafts, sets of overlapping disks on the shafts, rollers between the overlapping portions of the disks, a separate and independently-movable support for each roller, means for holding the 120 supports in substantial alignment, and means for pressing the rollers against the disks; and connections between said transmission-gear 125

and the part to be operated, substantially as described.

3. The combination with a part to be operated, of two pulleys and means connecting them with said part, a motor connected to operate one of said pulleys at a substantially constant speed, and means for driving the other pulley from that connected with the motor, said means being adjustable to vary the speed of the driven pulley, substantially as described.

4. The combination with a part to be operated, and a motor, of a frictional power-transmission gear comprising parallel overlapping friction-disks, and a friction-roller between the disks, the axis of rotation of which is substantially perpendicular to that of the disks, said roller consisting of a spindle with a plurality of revoluble parts thereon; and connections between said transmission-gear and the part to be operated, substantially as described.

5. The combination with a part to be operated, and a motor, of a power-transmission gear comprising driving and driven shafts, a plurality of overlapping parallel disks on each shaft longitudinally slidble thereon, rollers for frictionally engaging the sides of the overlapping portions of the disks, and means for pressing and holding the disks and rollers in frictional engagement; and connections between said transmission-gear and the part to be operated, substantially as described.

6. The combination with a part to be operated, and a motor, of a power-transmission gear comprising driving and driven shafts, a plurality of overlapping parallel disks on each shaft longitudinally slidble thereon, rollers for frictionally engaging the sides of the overlapping portions of the disks, means for pressing and holding the disks and rollers in frictional engagement, and means for varying the amount of frictional pressure between the rollers and disks; and connections between said transmission-gear and the part to be operated, substantially as described.

7. The combination with a part to be operated, and a motor, of a power-transmission gear comprising driving and driven shafts, a plurality of overlapping parallel disks on each shaft longitudinally slidble thereon, rollers for frictionally engaging the sides of the overlapping portions of the disks, means for pressing and holding the disks and rollers in frictional engagement, and means for simultaneously varying the positions of all the rollers on the faces of the disks to vary the relative speeds of the shafts; and connections between said transmission-gear and the part to be operated, substantially as described.

8. The combination with a part to be operated, and a motor, of a power-transmission gear comprising driving and driven shafts, a plurality of overlapping parallel disks on each

shaft, revoluble therewith but longitudinally slidble thereon, rollers for frictionally engaging the sides of the overlapping portions of the disks, and means for pressing and holding the disks and rollers in frictional engagement; and connections between said transmission-gear and the part to be operated, substantially as described.

9. The combination with a part to be operated, and a motor, of a power-transmission gear comprising driving and driven shafts, a plurality of parallel, overlapping disks on the shafts, all longitudinally movable, pairs of rollers between overlapping portions of pairs of disks whereby the shafts are rotated in opposite directions, and means for pressing the rollers against the disks; and connections between said transmission-gear and the part to be operated, substantially as described.

10. The combination with a part to be operated, and a motor, of a power-transmission gear comprising driving and driven shafts, a plurality of parallel disks all longitudinally movable on the shafts and revoluble therewith, pairs of rollers between the disks on one shaft and those on the other shaft, and means for pressing the rollers and disks into frictional contact; and connections between said transmission-gear and the part to be operated, substantially as described.

11. The combination with a part to be operated, and a motor, of a power-transmission gear comprising driving and driven shafts, a plurality of parallel disks on each shaft longitudinally movable thereon and revoluble therewith, pairs of rollers between the disks on one shaft and those on the other shaft, means for pressing the rollers against the disks, and means for simultaneously varying the positions of all the rollers on the disks; and connections between said transmission-gear and the part to be operated, substantially as described.

12. The combination with a part to be operated, of a motor, a driving-shaft, a driven shaft, pulleys on the shafts, an endless cable on the pulleys connected to said part, a plurality of overlapping disks upon the shafts, pairs of rollers between overlapping portions of pairs of disks for causing opposite rotation of the shafts, and means extending to and adjustable from the part to be operated for simultaneously varying the positions of the rollers on the faces of the disks to vary the relative speeds of the shafts, substantially as described.

13. The combination of a part to be operated, two pulleys connected therewith by flexible connections capable of traveling independently of said part and also of moving it in different directions, a single motor connected to drive one of the pulleys positively and continuously in one direction, and means controlled from said part to vary the speed of the other pulley, substantially as described.

14. The combination of a part to be operated, two pulleys connected therewith by flexible connections capable of traveling independently of said part and also of moving it in different directions, a single motor connected to drive one of the pulleys positively and continuously in one direction, means controlled from said part to vary the speed of the other pulley, and means extending to and operatable from said part to vary the speed of the pulley

driven from the motor, substantially as described.

In testimony whereof I have signed my name to this specification in the presence of two subscribing witnesses.

ETHELBERT M. FRASER.
